INVENTORS:

CARL A. BROWN,
ARTHUR M. KLINGMAN,
BY Albert G. Burio
THEIR ATTORNEY.

UNITED STATES PATENT OFFICE.

CARL A. BROWN, OF FOSTORIA, AND ARTHUR M. KLINGMAN, OF CLEVELAND, OHIO,
ASSIGNORS TO GENERAL ELECTRIC COMPANY, A CORPORATION OF NEW YORK.

ELECTRIC-LIGHTING FIXTURE.

1,246,047.

Specification of Letters Patent. Patented Nov. 13, 1917.

Application filed March 26, 1914. Serial No. 827,310.

To all whom it may concern:

Be it known that we, CARL A. BROWN, a citizen of the United States, residing at Fostoria, county of Seneca, State of Ohio, and ARTHUR M. KLINGMAN, a citizen of the United States, residing at Cleveland, county of Cuyahoga, State of Ohio, have invented certain new and useful Improvements in Electric-Lighting Fixtures, of which the following is a specification.

Our invention relates to electric lighting fixtures, and especially to fixtures which are designed for use outdoors, such as for street lighting.

An object of our invention is to provide a device of this kind in which the globe or shade surrounding the light source will be securely supported and at the same time the supporting structure be so constructed and so arranged with respect to the globe or shade that it will offer a minimum obstruction to the passage of the light rays. A further object of our invention is to provide a structure of the aforesaid character in which the supporting members will be effectually protected from the action of the weather. In order that our invention may be used in connection with lighting units evolving considerable heat, an object which we seek to obtain is the provision of proper ventilation without substantially detracting from weather protection. Still another object of our invention is to provide a supporting means which will allow the ready removal of the part of the globe supported by it for the purpose of cleaning. We seek also by our invention to attain the aforesaid objects by means of a simple and economical structure which may be conveniently attached or detached.

In carrying out our invention, we provide a two part inclosure or globe. The lower part or base is adapted to rest upon a support such as a post or other suitable means. The top part or cover, which is preferably of such construction and material that it will act as a reflector, is supported by the lower part and is detachably held thereto by means of a novel clamping means which is located substantially entirely within the globe. Preferably the said clamping means is an integral member and carries adjustable means for engaging the lower part of the globe and also the cover to hold the latter firmly in place or to allow its ready removal. Prefer-

ably, also, the clamping means carries means whereby the cover is spaced somewhat from the lower part so as to provide suitable ventilation, the parts of the globe being so shaped that the space therebetween is effectively protected from the weather.

Our invention will be more clearly understood by referring to the drawing, in which Figure 1 is an elevation, partially in section, of a fixture embodying our invention, and Fig. 2 is a perspective of a clamping member forming part thereof.

In Fig. 1 of the drawing is shown a globe consisting of a lower part or base 10 and an upper part or cover 11. Both of these parts may be of transparent or frosted glass, but it is preferred to have the base of frosted glass and the cover of white opalescent glass so that the former will be mainly diffusing in function, while the latter will be mainly reflecting. The base 10 is adapted to rest upon a post or to be otherwise supported by means not shown.

The cover is clamped to the base by means of the clamping member shown separately in Fig. 2. The said member is preferably of metal and composes a lower ring 12. Extending from downwardly projecting lugs 13 secured to said ring upwardly to a centrally disposed support on spider 14 in which they are firmly held, are a plurality of wires or rods 15. These rods should be as few in number and as small in section as is consistent with strength and wear so that they will obstruct as little light as possible. The ring 12 carries means which, as shown, are partially identical with the lugs 13 for engaging the base 10. This means, in addition to said lugs, comprises the adjusting screws 16 engaging with threaded apertures in said lugs. The ring 12 is also provided with the upwardly projecting spacing lugs 17. A pin 18 threaded at its upper end projects from the support or spider 14.

The cover 11 is preferably so shaped as to shed water and is of such width as to extend somewhat beyond the sides of the base 10. The bottom thereto is preferably reentrant as shown at 19. The said cover rests upon the lugs 17 which in turn rest upon the top edge of the base 10. A ventilating space 20 is thereby provided between the cover and base. The threaded end of pin 18 extends through a cap 22 resting on the said cover. A nut 23 which with the cap 22 may be orna-

rnental, engages therewith and securely clamps the ring 12 and attached part to the cover 11. The top of base 10 consists of an inwardly extending flange 24 against which the ends of screws 16 may be brought to bear to hold the cover 11 fast to the said base. In removing the cover 11, the nut 23 is unscrewed and removed with the cap 22 leaving the clamping member attached to the base 10. The clamping member may be removed by loosening screws 16.

It will be seen that substantially all of the metallic parts of the fixture are inclosed and thereby protected from the weather. The simplicity of the device and the convenience of its operation will also be apparent.

What we claim as new and desire to secure by Letters Patent of the United States, is:—

1. An inclosure for artificial light comprising a base, a cover having its lower edge adjacent to the upper edge of said base, a clamping member carried by the said cover and located substantially entirely within the same and adjustable means carried by the said clamping member for engaging the said base and holding the said cover thereto.

2. A clamping member for the purpose described comprising a substantially central pin, a ring surrounding the said pin, and rods connecting said parts, said ring carrying apertured lugs and screws engaging in said apertures from within said ring.

3. A clamping member for the purpose described comprising a substantially central pin, a ring surrounding the said pin, and rods connecting said parts, said ring carrying downwardly extending apertured lugs and screws engaging in said apertures from within said ring.

4. A clamping member for the purpose de-

scribed comprising a support, a ring surrounding the said support, and rods connecting said parts, said ring carrying downwardly extending apertured lugs and screws engaging in said apertures, and lugs extending upwardly from said ring.

5. A fixture comprising a glass globe having an upper or cover portion and a lower or base portion, the said upper or cover portion extending at least to the upper edge of the lower or base portion and being spaced therefrom, and a means constructed of metal substantially inclosed by the said globe and disposed substantially within the upper or cover portion thereof for clamping the cover to the base portion.

6. A fixture comprising a glass globe having a non-clear upper or cover portion and a light-transmitting lower or base-portion, the said upper or cover portion extending at least to the upper edge of the lower or base portion and being spaced therefrom, and a means constructed of metal substantially inclosed by the said globe and disposed substantially within the upper or cover portion thereof for clamping the cover to the base portion.

In witness whereof, I, the said CARL A. BROWN, have hereunto set my hand this 16th day of March, 1914, and I, the said ARTHUR M. KLINGMAN, have hereunto set my hand this 24th day of March, 1914.

CARL A. BROWN.
ARTHUR M. KLINGMAN.
